UNITED STATES PATENT OFFICE.

JOHN L. KUNTZ, OF OMAHA, NEBRASKA.

CORNER-PIECE FOR FRAMES.

1,016,278.

Specification of Letters Patent.

Patented Feb. 6, 1912.

Application filed August 19, 1911. Serial No. 644,994.

To all whom it may concern:

Be it known that I, JOHN L. KUNTZ, a citizen of the United States, residing at Omaha, in the county of Douglas and State of Nebraska, have invented certain new and useful Improvements in Corner-Pieces for Frames, of which the following is a specification.

This invention relates to a corner piece for screen frames, and has for its principal object to provide a holder of integral construction, which may be conveniently and economically formed from sheet metal, for securing, in rigid relation, the horizontal and vertical strips of the frame.

Another object is to provide corner pieces so constructed that they may be firmly connected to the sides of the frame between the outer and inner faces thereof, so that the screen frame may be planed or reduced in size to correspond to the opening of the window frame.

The invention includes a corner piece for securing together the terminals of the horizontal and vertical strips of a frame, said corner piece being formed by incising a small, square, metallic sheet to provide two side plates with terminal outer and inner flanges, said side plates being adapted to embrace the sides at the terminals of the strips, and providing a bridge to span the space near the junction and between the inner faces of the horizontal and vertical strips, the terminal outer flanges of the side plates engaging within channels or slots formed in the sides of the strips, the inner flanges and free edges of the bridge bearing upon the inner faces of said strips.

The invention consists of the novel construction, combination and arrangement of parts as described herein and claimed, and as illustrated in the drawing wherein,—

Figure 1 is a perspective view of a corner piece embodying my invention. Fig. 2 is a view of the inner end or side of the same. Fig. 3 is a side view of the horizontal and vertical strips of a frame with the corner piece mounted thereon. Fig. 4 is a transverse section on line *a a* of Fig. 3. Fig. 5 is a diagrammatic view showing a square metallic sheet incised to form the corner piece.

Referring now to the drawing for a more particular description, the adjacent, terminal portions of the angularly disposed horizontal and vertical strips of a frame are re-

spectively indicated at 6 and 7, said strips preferably being rectangular in cross-section and provided with grooves or channels 8 to form longitudinal portions *b* outwardly of the grooves, these portions being provided so that the frame may afterward be reduced to correspond to an opening, within which it may be disposed.

To provide a corner piece for securing together the ends of strips 6 and 7, I employ a single, substantially square, metallic sheet, shown best in Fig. 5, incised diagonally on alining lines *c c* and *c c* from two of its opposite corners in directions of its middle, to form the two triangular side plates 9 and 10, and incised near its middle on adjacent lines *e f*, at right angles to lines *c c*, to provide a bridge member 11, plates 9 and 10 being bent on the broken parallel lines *f f* and *e e* at right angles to the bridge member; plates 9 and 10 near their outer edges are then bent inwardly as indicated by the broken lines *c g c* to form the outer longitudinal flanges 12; and four inner, triangular flanges 13 are formed by bending portions of plates 9 and 10 inwardly on the broken lines *f h* and *e h*. The corner piece thus formed provides a very strong construction, and when mounted in operative position, plates 9 and 10 embrace the sides of the frame strips, flanges 12 being seated within grooves 8, the inner flanges 13 engaging the inner faces of the strips, bridge member 11 spanning diagonally the space adjacent to the terminals and between the inner faces of the horizontal and vertical frame-strips.

It is obvious that after the corner piece is mounted as described, flanges 12 and 13 and bridge 11 will operate to resist any stresses or strains tending to change the angular relation of the frame strips. Practically no material is cut to waste in forming the corner piece, substantially all of the square sheet shown in Fig. 5 being utilized to form the side plates, bridge and flanges. By reference to Fig. 3 it will be seen that, when the sheet is incised and bent as described, wings or projections *j* are formed which extend outwardly of and to reinforce the bridge, and the free edges of the bridge are adapted to make contact with the inner faces of the frame strips.

In practice, the corner pieces are mounted upon the frames at the time of manufacture, and keepers or nails 14 are at that time

driven through the side plates into the strips; and portions *b* of the frame strips may afterward be reduced, if desired, for the purpose mentioned.

5 Having fully described my invention, what I claim and desire to secure by Letters Patent is,—

1. In combination with the horizontal and vertical strips of a frame, said strips being 10 formed with channels in their sides, a corner piece comprising a metallic sheet incised and bent to form substantially parallel side plates with outer and inner terminal flanges, and a bridge connecting the side plates; said 15 corner piece adapted to have a mounting with its side plates embracing the sides of the frame strips, its outer terminal flanges being seated in the channels, its inner flanges engaging the inner faces of the strips, said 20 bridge spanning the space adjacent to the terminals diagonally between the inner faces of said frame strips.

2. In combination with the angularly disposed strips of a frame, said strips having 25 grooves formed in their sides, a corner piece therefor consisting of substantially parallel, adjacent, triangular plates integrally connected by a bridge member and provided with outer and inner inturned flanges; said 30 corner piece adapted to be disposed with its triangular plates embracing the sides of the frame strips, its outer flanges being seated in said grooves, its inner flanges engaging the inner faces of said strips, said bridge 35 member extending diagonally between and having its ends bearing upon the inner faces of said frame strips.

3. In combination with the horizontal and 40 vertical strips of a frame, a corner piece comprising a metallic sheet incised and bent to form side plates with wings and with

outer and inner transverse flanges and a connected bridge-member; said corner piece adapted to have a mounting with its side plates embracing the sides of the frame 45 strips, its outer transverse flanges being seated in the sides between the inner and outer faces of the strips, its inner flanges engaging the inner faces of said strips, said bridge-member extending diagonally between with its free ends engaging the inner faces of said strips, the wings of said plates extending outwardly of the bridge-member for engagement with the sides of the frame strips. 55

4. In combination with the horizontal and vertical strips of a frame, a corner piece therefor comprising a metallic sheet incised and bent to form triangular plates for a seating upon the sides of said strips, and a 60 transverse brace for spanning the space between and near the junction of the inner faces of said strips, said side plates having wings extending outwardly of the brace for engagement with the sides of said strips. 65

5. In combination with the horizontal and vertical strips of a frame, a corner piece therefor, comprising a metallic sheet incised and bent to form triangular side plates with 70 terminal wings and a transverse bridge; said side plates adapted to have seatings upon the sides of the strips to dispose said bridge adjacent to the junction and between the inner faces of said strips, said wings 75 projecting outwardly of the bridge for engagement with the sides of said strips.

In testimony whereof I have affixed my signature in presence of two witnesses.

JOHN L. KUNTZ.
